UNITED STATES PATENT OFFICE.

JOHN A. FISH, OF MELROSE, MASSACHUSETTS.

DESIGN FOR A HOT-WATER HEATER OR BOILER.

SPECIFICATION forming part of Design No. 25,213, dated March 3, 1896.

Application filed January 9, 1896. Serial No. 574,912. Term of patent 14 years.

To all whom it may concern:

Be it known that I, JOHN A. FISH, of Melrose, in the county of Middlesex and State of Massachusetts, have invented and produced 5 a certain new and original Design for Hot-Water Heaters or Boilers, of which the following is a specification, reference being had to the accompanying drawings, forming a part hereof.

10 Figure 1 represents a perspective view of a water heater or boiler embodying my design. Fig. 2 represents a horizontal section of the same on line 2 2 of Fig. 1.

15 The leading features of my design are a base, a series of vertical columns extending upwardly from said base and arranged in a circular series, two of the columns being separated by a space which is wider than the spaces between the other columns, and a 20 dome surmounting said columns.

In the drawings, *a* represents the base. *b* represent the vertical columns, which

extend upwardly from the base and are arranged in a circular series, two of the columns being separated by a space 7 of greater ²⁵ width than the spaces between the other columns.

c represents the dome which surmounts the columns *b*.

The dome and base extend outwardly from the columns, the outer portions of the columns being within the margins of the dome and base.

I claim—

25 The design for a hot-water heater or boiler, substantially as shown and described.

In testimony whereof I have signed my name to this specification, in the presence of two subscribing witnesses, this 26th day of December, A. D. 1895.

JOHN A. FISH.
